LETTER DROP FOR MAIL CHUTES

Stanley V. Van Riper, New Rochelle, N. Y., assignor to Cutler Mail Chute Co., Rochester, N. Y., a corporation of New York

Application February 27, 1933, Serial No. 658,710

2 Claims. (Cl. 232—45)

My present invention relates to mail chutes and mail boxes and more particularly to letter drops therefor, and it has for its general object to provide a simple, practical and efficient mailing aperture construction that will be effective to prevent postal packages and other objects of a larger size than the chute is intended to handle from being crowded into the mailing aperture and causing stoppages that clog the chute against further immediate use from the floor or level at which the objectionable article is inserted and from the floors above. The improvements are directed in part toward providing means for intercepting at the mailing aperture expandable articles, such as large folded envelopes or folded newspapers which otherwise might be crowded in only to later spring open and toward the provision of further means, making it convenient for persons having even limited authority to quickly remove the intercepted package and restore service. A further object of the invention is to advantageously combine the foregoing functions with a trash ejector, such as that disclosed in my prior Patent No. 1,907,906, dated May 9, 1933, the application for which was copending with this application. To these and other ends, the invention resides in certain improvements and combinations of parts, all as will be hereinafter more fully described, the novel features being pointed out in the claims at the end of this specification.

In the drawings:

Fig. 1 is a front elevation of a section of a mail chute provided with a letter drop constructed in accordance with and illustrating one embodiment of my invention;

Fig. 2 is an enlargement of a fragment of the chute, as shown in Fig. 1, together with the letter drop construction thereof;

Fig. 3 is a view corresponding to Fig. 2 but with the door or front of the letter drop casing shown fully opened;

Fig. 4 is a substantially central vertical section taken on Fig. 2 with the parts in normal position;

Fig. 5 is a duplication of the showing of Fig. 3, except that the front wall plate of the mailing throat has been removed;

Fig. 6 is a duplication of the showing of Fig. 4, except that an objectionable piece of mail matter is shown caught in the arresting device;

Fig. 7 is a further enlarged horizontal section taken substantially on the line 7—7 of Fig. 4;

Fig. 8 is a horizontal section on the same scale taken substantially on the line 8—8 of Fig. 4;

Fig. 9 is a fragmentary detail section through

the trash discharge opening taken substantially on the line 9—9 of Fig. 4, and

Fig. 10 is a duplication of a fragment of the showing of Fig. 7, showing the lock in a different position.

Similar reference numerals throughout the several views indicate the same parts.

The general nature and functions of a mail chute are too well known to require extended explanation here. In Fig. 1 is shown one section or unit as installed on a single floor of an office building or the like forming part of a continuous chute extending vertically through the building and terminating in a collection box on the ground floor. The section comprises ceiling and floor connections 1 and 2, a backing 3, to which the chute channel proper 4 (Fig. 7) is suitably secured, and glass front panels 5 held in moldings 6 that fit the channel. These panels are usually made removable and are locked in place by a suitable key controlled locking bar 7 which may be manipulated only by authorized persons representing the Postoffice Department. It is through these panels that the stoppages are reached and cleared.

The lower panel of each section is fitted with a letter drop and, in the practice of my invention, as shown in the present embodiment thereof, such fixture embodies a casing having a back plate 8 and side walls 9. Lateral appropriately shaped lugs 10 on the back plate are confined within the panel beads or moldings 6 to support the casing in fixed position. The front thereof is displaceable and, in the present instance, is in the form of a door 11 hinged to the backing 8 at the bottom, as indicated at 12, so that it can be swung from the normal position of the other figures to that of Fig. 5. The door or front has lateral flanges 13 that normally overlap the side walls 9 and a top flange 14 that abuts the backing. The exteriorly accessible mailing opening 15 is formed in this flange. A suitable lock 16, key controlled, (Figs. 7 and 10) is mounted in one of the side flanges 13. It is shown, in the present instance, as a rotary lock, the barrel 17 of which is also longitudinally movable in the manner of the familiar ignition lock for automobiles and terminates in a bolt 18 taking into a keeper opening 19 in a side wall 9 of the casing. As will further appear, the opening of the door or front 11 affords but limited access to the interior of the chute so that custody of the key to lock 16 can well be entrusted to a semi-authorized person, such as the superintendent of the building in which the chute is installed.

Leading downwardly at an inclination from the mailing or drop opening 15 is a throat 20 through which envelopes and other intended mailable matter slide to the main channel 4. This channel lies between a front plate 21 fastened to the sides 9 of the casing at 22 and a back plate 23 abutting the back plate 8 of the casing and having forwardly extending flanges 24 at its sides, by means of which it is also fastened at 25 to the side walls. Both ends of this back plate, as well as the lower edge of the front plate 21 are so disposed as to constitute letter sheds for mail matter descending from a higher level.

The front wall 21 of the throat is relatively short, is spaced from the door by a lug 26 and thereby provides an opening or passage 27 leading from the throat 20 to the forward interior space 28 of the letter drop casing, at the bottom of which space or chamber is a discharge opening 29 leading back to the exterior of the chute. This is for the purposes fully explained and claimed in my copending application, aforesaid, namely, cigarette ends and other small trash dropped into the mailing opening 15 strike a swinging deflector 30 pivoted at 31 at the rear of the throat and normally lying across the latter, as shown in Fig. 4, by which deflector they are thrown forwardly through the opening 27 and into the space 28 which is sealed from the chute and from which they discharge through opening 29. The deflector 30 is readily displaced, however, as shown in Fig. 6, upon receiving the thrust of letters or other longer mail matter. The throat 20 is also partially defined by spaced letter guiding ribs 32 on the inner side of the door 11 that continue in the plane of the front plate 21 in the region of trash passage 27.

The lower edge of the back plate 23 is serrated and bent upwardly and forwardly in a plurality of prongs or fingers 33 that stand out therefrom but are spaced from the front plate 21 sufficiently to preserve the continuity of throat 20 while limiting its capacity to accommodate mail matter of proper size and intended thinness. Pivoted by means of forwardly projecting ears 34 thereon to the side walls 9 at 35 is a swinging yielding guard plate 36 much like the deflector 30 above it. This guard plate 36 normally hangs in the position shown in Fig. 4, acting as a shield for the fingers 33 to shed proper light mail matter away from them as such matter passes down the throat 20. When, however, a heavy package of too great thickness to safely traverse the chute is jammed down the throat, the guard yields and the fingers arrest such package, as shown in Fig. 6, before it can get into the chute at all. Such figure shows at E a large envelope that has been folded for insertion in the mailing opening 15, but which, reacting

against the plate 21, has expanded displacing the guard plate 36 and has become entangled with the detector finger 33. In such a case, that particular drop is temporarily out of service, which fact, aside from the inability to deposit other pieces, is discernible through openings or windows 38 in the displaceable front 11. In such a situation, the superintendent simply unlocks the front 11, swings it down, as in Fig. 5, extracts the objectionable piece and returns it to the depositor or redeposits it in a more suitable mail collecting receptacle. It is apparent from the drawings in general that such an operation does not give access to the chute in such a way or to sufficient extent that the mail can be tampered with and hence, as before suggested, full postal authority can well be dispensed with.

As appears in Fig. 6, the trash deflector 30, because of its curvature and its abutment against the back plate 23, acts, in conjunction with an inclined transverse rib 39 to shed the mail matter past the upper edge of the shield 36 with which it might otherwise engage.

I claim as my invention:

1. In a letter drop for mail chutes, the combination with a casing having a mail receiving opening at the top and a trash chamber at the bottom, and provided with a throat embodying a front wall having an opening therein leading to the trash chamber, of a yielding trash diverting element normally blocking the throat to deflect light trash to the trash chamber but displaceable by the contact of mail matter, a package arresting device in the throat below said element, and a guard normally shielding said device from engagement with envelopes and other relatively thin mailable matter, the front of the casing being displaceable to permit access to the throat when clogged and to the trash chamber.

2. In a letter drop for mail chutes, the combination with a casing having a mail receiving opening at the top and a trash chamber at the bottom, and provided with a throat embodying a front wall having an opening therein leading to the trash chamber, of a yielding trash diverting element normally blocking the throat to deflect light trash to the trash chamber but displaceable by the contact of mail matter to lie against one side of the throat, a package arresting device in the throat below said element, and a pivoted guard plate also below said element on the same side of the throat normally shielding said device from engagement with envelopes and other relatively thin mailable matter, the trash diverting element being adapted when displaced to act as a shed for the upper edge of the guard plate.

STANLEY V. VAN RIPER.
